UNITED STATES PATENT OFFICE.

GEORGE W. FROST, OF COLUMBUS, OHIO.

STORAGE-BATTERY GRID.

SPECIFICATION forming part of Letters Patent No. 757,396, dated April 12, 1904.

Application filed February 9, 1904. Serial No. 192,831. (No model.)

To all whom it may concern:

Be it known that I, GEORGE W. FROST, a citizen of the United States, residing at Columbus, in the county of Franklin and State of Ohio, 5 have invented certain new and useful Improvements in Storage-Battery Grids, of which the following is a specification.

This grid is intended for use in lead storage batteries, and is designed to securely hold 10 a maximum amount of active material with a minimum exposed surface. The grid is constructed to provide a large contact-surface between the metal and active material and to have great rigidity with the least possible 15 weight.

The grid comprises a rectangular frame, a series of retaining-strips extending between the sides of the frame at each face of the grid, the strips of the two series being relatively 20 staggered, and a horizontal web extending from each strip substantially through the grid.

The grid is provided with a terminal lug having a flanged head, which enables the adjacent electrodes of like sign to be readily and 25 permanently connected by a burned joint.

Referring to the accompanying drawings, Figure 1 is a perspective view of the grid with a portion broken out. Fig. 2 is a transverse 30 vertical section of the grid and the filling of active material. Fig. 3 is a detail vertical section of the upper portion of the unfinished cast grid. Fig. 4 is a vertical section of the same portion after it is finished, and Fig. 5 is 35 a detail perspective view showing the flanged terminal heads of several electrodes burned together.

The grid 1, which is preferably cast of pure lead, comprises a rectangular frame 2, a series 40 of retaining-strips 3, extending between the sides of the frame at each face of the grid, the strips of the two series being relatively staggered, and an integral horizontal web 4, extending from the middle of each retaining-strip to the other face of the grid. The webs 45

preferably taper slightly from the strips 3 to their edges to facilitate stripping of the cast grid from the mold. The retaining-strips are cast as thin as is practicable, the usual thickness being 0.06 of an inch. This thickness is

greater than is required to give the grid the necessary rigidity, and the cast grids are therefore passed under a broad milling-cutter, which removes 0.03 of an inch from each side of the plate. The thickness of the cast grid, 55 which is usually 0.32 of an inch for heavy stationary cells, is thereby reduced to 0.26 of an inch, and the weight of the grid is thereby decreased about one-third. For automobile-batteries the grids are cast 0.25 of an inch 60 thick and milled down to 0.19 of an inch. As the milling-cutter passes over the surface of the plate it leaves narrow burs or flanges 5 at the edges of the retaining-strips 3 and webs 4. These flanges are of service in retaining 65 the active material in the grid. Grids of considerable size are stiffened by one or more vertical intermediate ribs 7, extending from the top to the bottom of the grid. Three such stiffening-ribs are shown in Fig. 1. The active 70 material 6 is forced into the grid through the small slits while in a plastic condition and is then hardened. The electrodes are formed in the usual manner.

The terminal lug 8 of each grid is provided 75 with a laterally-flanged head 9. The intermediate electrodes have a double-flanged or T-shaped head 9. The end electrodes have a single-flanged head 10. These heads have parallel edges and are of such width that the adjacent edges register when the electrodes are properly spaced apart. These heads enable 80 perfect connections to be made between the electrodes. The two clean edges of the heads of adjacent electrodes are simply brought together, a mold placed around the under part, and an oxyhydrogen flame applied at the top. The lead is thus melted entirely through and upon cooling produces a perfect smooth joint 85 11. A connector-strap 12 is cast integral with 90 the head of one of the grids, so that in a five-plate cell, for example, there are but three joints, and these joints are substantially perfect and will resist the action of acid for an indefinite period.

The distribution of the metal of the grid is such as to give it great rigidity with the least possible weight. The space available for active material amounts to from fifty to seventy per cent. of the total volume of the electrode, 95 100

and the weight of the active material in portable batteries may be fifty per cent. of the total weight of the electrode. After the active material is forced into the grid and hardened it is practically impossible to remove it. It is therefore unnecessary to employ separators of asbestos or fabric. The exposed surface of the active material is reduced to a minimum of about forty per cent. of the total surface of the electrode, and the lead surface of the grid greatly increases the capacity of the plate as it becomes oxidized during use. Careful tests have shown that the exposed surface of the active material is sufficient to give ready access to the electrolyte and that the cells will charge and discharge with an efficiency equal to that of any cell having pasted plates. The retaining strips and webs not only prevent the plate from buckling, but give a large contact-surface, so that current is readily carried to or taken from the active material. The design of the grid is also such that it expands evenly as the active material increases in volume.

25 The grid can be cast in a simple and inexpensive mold, and a workman can cast several hundred grids of medium size in a day.

I claim—

1. A double-lattice battery-grid, comprising a frame, retaining-strips on the opposite faces and in staggered relation, and a web extending from each strip substantially through the grid, as set forth.
2. A battery-grid, comprising a rectangular frame, a series of retaining-strips extending between the sides of the frame at each face of the grid, the strips of the two series being relatively staggered, and a horizontal web extending from each strip substantially through the grid, as set forth.
3. A battery-grid, comprising a rectangular frame, a series of retaining-strips on the opposite faces and in staggered relation, and a web extending from each strip substantially through the grid, as set forth.

lar frame, a series of retaining-strips extending between the sides of the frame at each face of the grid, the strips of the two series being relatively staggered, and a horizontal, 45 median web extending from each strip substantially through the grid, as set forth.

4. A battery-grid, comprising a rectangular frame, a series of retaining-strips extending between the sides of the frame at each 50 face of the grid, the strips of the two series being relatively staggered, a horizontal, median web extending from each strip substantially through the grid, and an intermediate, vertical stiffening rib or ribs extending from 55 the top to the bottom of the grid, as set forth.

5. A battery-grid, comprising a rectangular frame, a series of retaining-strips extending between the sides of the frame at each face of the grid, the strips of the two series 60 being relatively staggered, a horizontal web extending from each strip substantially through the grid, and burs or narrow flanges on the edges of said strips and webs, as set forth.

6. A battery-grid, comprising a frame, retaining-strips on the opposite faces and in staggered relation, a web extending from each strip substantially through the grid, and a terminal lug having a laterally-flanged head. 70

7. A pair of battery-electrodes, each electrode having a terminal lug with a lateral, relatively thin, broad flange, the adjacent edges of said flanges being fused together, as set forth.

In testimony whereof I affix my signature in presence of two witnesses.

GEORGE W. FROST.
